CRATE CONVEYER

Alvin Lenhart Eshelman, Upland, Calif.

Application April 23, 1949, Serial No. 89,337

1 Claim. (Cl. 198—162)

1

This invention relates to novel apparatus for conveying articles. More particularly, the invention relates to apparatus for the movement of articles having resilient walls capable of temporary lateral deflection from their normal planes at portions intermediate the ends of such walls. While the apparatus of the present invention may be employed solely for the purpose of conveying articles of the kind described from point to point, it is more particularly an object of the invention to provide a conveyer in which the resilient-walled articles are positively maintained in upright position by the conveyer apparatus while labels or trade brand stickers, for example, are applied to the upper ends of the articles simultaneously with the advancement of the articles.

The invention has particular utility in the application of labels to the heads or ends of citrus fruit or other produce crates or boxes of the type which are generally used for shipping such produce to market. Because there has heretofore been no convenient and simple apparatus for applying labels to pre-assembled crates of the kind described, it has been customary for the sake of economy and where possible, as in the case of orange crates for example, to apply the labels to the heads or ends before the latter are assembled into crates. Typical apparatus for this is shown and described in U. S. Patent No. 1,652,698. There is the disadvantage in such practice, however, that subsequent handling of the labeled crate heads during assembly of the crate is apt to tear or otherwise disfigure the label and thus detract from its advertising and display value. In many cases, however, it is entirely impractical to apply the labels to the crate heads before assembly. This is true, for instance, in the lemon packing industry, since it is customary in this industry to use, for shipping purposes, so-called "dirty crates" which have previously been employed for storing the fruit during ripening and coloring periods. Obviously it would be totally impractical in such case to label the crates before assembly, since the dirt and mold which they accumulate during the storage period would seriously, if not completely, impair the appearance of the labels by the time the crates were shipped to market. The labeling of lemon crates must, therefore, be done after the crates have been fully assembled and it would of course be desirable to label all crates in the same way if it could be economically and conveniently accomplished.

2

It is an object of the present invention, therefore, to provide a conveyer which facilitates the application of labels to the ends of pre-assembled but unpacked crates or boxes. As is commonly known, crates of the type which are used for shipping produce to market are composed of head or end pieces and a plurality of side members connected at their ends to such heads to provide a box having slatted sides. Usually the head or end pieces are of relatively thick wood, on the order of three-fourths of an inch for example, while the side members are of much lighter material, normally about five-sixteenths of an inch thick. These latter are purposely designed to permit a limited amount of lateral deflection to take place in the sides of the complete crate in order to more readily accommodate it to the particular produce with which it is packed. In some instances, especially in crates of the larger size such as are used for oranges, for example, a central header or divider, usually of the same thickness as the crate ends, is also employed to give added strength to the crate. However, even in this case lateral deflection of the side wall members intermediate the points of connection to the ends and central partition may and does occur when the crates are packed.

It is a further object of the present invention, therefore, to provide a conveyer for crates of the type herein discussed, whereby the positioning and supporting of these crates, while brand markers are applied to their ends prior to the packing of the produce into these crates, is easily and simply accomplished by taking advantage of the natural resilience of the side members in order to effectively grip and hold them firmly while the brand markers are applied. Essentially, the apparatus for this purpose may consist of a runway along which the crates, in up-ended position, are advanced by means disposed on opposite sides of this runway, such advancing means being permanently maintained in spaced-apart relationship a distance which is appreciably less than the normal width at that point of the crate being advanced, whereby the side walls of the crates are temporarily deflected inwardly at their intermediate portions by the advancing mechanism during the travel of the crates through the labeler. In this manner, each crate is gripped and carried along while it is held in up-ended position and the application of the labels at the labeling point or station is greatly facilitated. It is apparent, of course, that the crate must

be firmly supported in its up-ended position, this position naturally being a very unstable one, to prevent the tipping of the crate by the operations of applying an adhesive and the label.

Normally, the labeling unit of the present invention will be incorporated into a conventional conveyer system as a section or unit of such system. A typical installation embodying a commercially desirable form of the invention comprises a runway along which the boxes or crates are progressed in up-ended position by means of one or more pairs or sets of endless belts or chains, the belts or chains of each set being disposed for travel in a horizontal plane on opposite sides of such runway. As previously mentioned, these endless belts or chains are so positioned relative to the path of the articles that the inner or adjacent runs of each set are fixedly spaced apart horizontally a distance which is less than the normal width of a crate. In the case of orange crates, for example, which normally have two compartments separated by a central header or partition, it is usually preferable to provide two such sets of opposed endless chains, one set engaging the crates at substantially the midpoint of the upper compartment while the other set engages it similarly in the lower compartment. The installation may also preferably include a lower supporting track upon which the lower ends of the crates slide as they are advanced by the endless chains, or such track may itself be an endless belt, for example, which is driven in unison with the endless side chains thereby serving to assist in the progression of the articles. It is to be understood, however, that such lower track is not indispensable to the successful operation of a conveyer embodying the present invention, for in many instances the set or sets of opposed side chains will entirely serve to support the crates as well as to advance them. This is especially true where the crates are comparatively light and it is desired to have free access to both ends of the crate for applying labels simultaneously by automatic means to both of such ends.

In the particular example hereinafter illustrated and described, the novel labeler described includes glue applying mechanism operating in timed relation with the advance of the boxes or crates and is designed for manual application of the labels to the up-turned ends of the crates; but it is also possible, of course, to provide means for effecting the application of the labels entirely automatically.

As crates of the type here being considered are usually conveyed while lying in their prone position, this being the most stable condition of course, some provision must be made for up-ending the crates successively as they arrive at the initial end of the labeling unit. And similarly, means must also be provided at the discharge end of such section for laying the crates down onto their sides again for further travel on conventional conveyers. These operations may be easily accomplished, for example, by providing a step-down from the conventional conveyer to the runway of the labeling unit at the initial end of the latter so that the crates are deposited thereon in an upright position. At the discharge end of this unit, where the crates are delivered once again to the conventional type of conveyer, a deflector positioned in the path of the advancing crates will serve to tip the crates back into their prone position for further travel.

A further understanding of the operation of

the present invention will be had from the detailed description of a particularly suitable commercial form of the invention illustrated in the accompanying drawings, in which

5 Fig. 1 is a view in plan of the novel crate labeling conveyer section;

Fig. 2 is a view in side elevation taken along line 2-2 of Fig. 1;

Fig. 3 is a sectional view in end elevation taken 10 on line 3-3 of Fig. 2;

Figs. 4 and 5 are fragmentary views in perspective illustrating certain details of the adhesive applicator shown in Fig. 2;

Fig. 6 is a view in side elevation of a means 15 for depositing crates in upright position as they arrive at the labeling section;

Fig. 7 is a view in end elevation of the arrangement shown in Fig. 6; and

20 Figs. 8 and 9 are views in side and end elevation, respectively, of means for tipping the crates back onto their sides after leaving the labeling conveyer section.

The apparatus illustrated in the accompanying drawings is adapted for the handling of boxes or crates of the type commonly employed for shipping oranges, grapefruit and the like to market. As has been explained hereinabove, crates of this type are constructed in such manner that their sides, which are of relatively 25 light material, are capable of some bending or flexing intermediate the points at which the side members are nailed or otherwise secured to the crate ends and central divider. In the present instance, the crates, indicated generally 30 at C, consist of end pieces 20, central divider 21, side members 22 and bottom members 23. As shown in the drawings, crates C are divided into two compartments 24 by partition 21, and the top or face of the crate, opposite members 23, 35 is left open to permit the fruit to be later packed at C, into the crate. Apparatus for handling the crates during the labeling operation is indicated generally at 25 and comprises a supporting framework 26 upon which the crate advancing means are mounted. Delivery of the crates to the 40 labeling unit is provided by means of a conventional endless conveyer 27 by which the crates are advanced on their sides with the open faces all looking in the same direction, as shown in Figs. 6 and 7. This delivery conveyer intersects 45 the path of the crates in labeler 25 at right angles and its discharge end is positioned above the lower supporting run of the crates in the labeling unit so that the crates are up-ended as they roll off the end of conveyer 27. Interference between the crates as they come off the end of 50 conveyer 27 is avoided by positioning the discharge end of the latter above the runway of the labeling unit a distance substantially equal to the height of the crates being handled. A guard 55 rail 28 opposite the discharge point of conveyer 27 further assists in deflecting the crates into upright position as they come off of conveyer 27. Crates C are thus deposited on a short-run feed 60 conveyer 29 which advances them to labeling unit 25. As thus delivered, the open sides of the crates face in the direction of travel through the labeling unit and sides 22 of the crates are 65 parallel to the longitudinal axis of the unit.

70 Referring now to Figs. 1 and 2, labeling unit 25 includes pairs or sets of endless chains 30, the chains of each set being disposed on opposite sides of the runway for travel in a horizontal plane. In the particular illustration here shown there are two such sets, one above the other, whose respective planes of travel substantially

bisect the upper and lower compartments 24 of crates C. As crates C are advanced by feed conveyer 29, they pass between chains 30 of the two sets and are gripped at their sides so as to hold them rigidly in their upright position as well as to cause them to be advanced with the chains. In order that successive crates will be spaced apart from each other a small distance during their travel through conveyer section 25, this being desirable for the purpose of facilitating the application of the labels to the upper ends of the crates, chains 30 are driven at a linear speed slightly greater than that of feed conveyer 29 so that as the crates are discharged from the feed conveyer there is a momentary acceleration which serves to effect the aforesaid spacing of the crates. While in many instances it will be unnecessary to provide any support at the lower ends of the crates as they are carried along labeler 25, it is usually preferable to provide some support, such as conveyer 31 shown in the drawings. This conveyer consists of an endless belt 32 which is driven in unison with the side chains 30 and on which the lower ends of the boxes rest as they pass through the label applicating station.

Each side chain 30 is trained about a pair of sprockets 33, 34, which are supported near the opposite ends of the labeling section upon shafts 35, 36, respectively. Shafts 35 and 36, in turn, are journaled for rotation in the vertical plane in bearing blocks 37 and 38, respectively, mounted on frame 26. As shown more particularly in Fig. 3, chains 30 are provided with backing rails 39 which extend along unit 25 the entire distance between sprockets 33 and 34. The rails are supported upon frame 26 by suitable brackets and are composed of a central wood longeron 40 enclosed at its upper surface and opposite edges by a wide-webbed channel 41. At the inner run 30a of chains 30, the flange of channel 41 serves as a backing for this run of the chains. Rails 39 are also provided with an angle iron 42 secured along their outer edge which acts as a supporting track for the outer or return run 30b of the chains. The web of channel 41 is made sufficiently wide so as to act as a guard over the return run of chains 30. As will be seen from the drawings, inner runs 30a in each set of horizontally opposed chains 30 are fixedly held in spaced-apart relation by rails 39 a distance which is appreciably less than the normal width of crates C so that as the crates pass between chains 30, their sidewalls 22 are deflected inwardly and the crates thereby are securely gripped between the inner runs 30a of each set of chains 30. The inner runs 30a present straight virtually continuous faces to the walls of the crates for continuous uniform engagement therewith along parallel lines of contact. The brackets upon which rails 39 are mounted are provided with means, not shown, whereby the rails may be adjusted toward or away from each other across the labeler and then secured to effect the desired amount of deflection in sidewalls 22 of the crates.

Endless belt 32 of the lower supporting conveyer 31 is trained about drums 43 and 44 which are secured to horizontally supported shafts 45, 46, respectively, at opposite ends of unit 25. Shafts 45 and 46 are journaled in suitable bearing blocks mounted on frame 26, as are idler rollers 47 which extend transversely across the conveyer as a support for the upper run of belt 32.

Driving power for the apparatus is provided by

motor 48 mounted on frame 26. Shaft 49, which is the main driving shaft of the unit, is connected to motor 48 by means of a chain and sprocket connection consisting of sprockets 50, 51 and chain 52. Shaft 49 passes through and is journaled in a pair of right-angle drives 53 mounted atop the labeler frame. Shafts 36 are the driving shafts for side chains 30 and are driven from shaft 49 by means of bevel gearing enclosed within in the housing of right angle drives 53. Power is also supplied through shaft 49 to the driving drum 44 of the lower supporting conveyer 31 by means of a sprocket 54, chain 55 and sprocket 56, the driving connection being such that the speed at which belt 32 travels is the same as that of side chains 30. Power for driving conveyer 29 is obtained by a take-off sprocket 291 secured to shaft 45, and a driven sprocket 292 on drum 293 through a chain connection 294. As previously mentioned, it is desired that conveyer 29 travel at a slightly lower speed than conveyer 31 and this is accomplished by making driven sprocket 293 of slightly larger diameter than its driving sprocket 291.

It will be apparent from the foregoing that, in operation, crates C are advanced by conveyer 27 and are deposited on end on conveyer 29 at the rear of labeling unit 25 with the open faces of the crates forward. From there the crates are advanced by short feed conveyer 29 to be picked up by the cooperating side chains 30 and lower supporting conveyer 31 of the labeling unit. The crates then progress through the labeling unit while held rigidly supported in their upright position as they are advanced, a secure grip being obtained by the slight inward deflection of side members 22 where they are contacted by chains 30.

The means incorporated in the present unit for applying an adhesive or paste to the upper ends of advancing crates C is indicated generally at 57 in the drawings. As will be seen, the applicator is supported above the initial end of unit 25 and comprises a paste tank 58 suspended from uprights 59 on frame 26 so as to permit paste to flow by gravity from dispensing outlet valves 60 directly onto the upper surface of a revolving brush 61. This brush is of sufficient length to extend across substantially the full width of crate head 20. Brush 61 is mounted on a vertically adjustable shaft 62 directly over the path of the crates and is positioned so that the bristles of the brush contact the upper heads 20 of crates C as they pass beneath the brush. In order to properly control the amount of paste delivered to brush 61, dispensing valves 60 are cyclically operated in timed relation to the speed of side chains 30 and lower supporting conveyer 31. Driving power for both brush 61 and the operation of valves 60 is obtained from a take-off sprocket 63 secured to shaft 45 of conveyer 31. Chain 64 transmits power from sprocket 63 to sprocket 65 which is secured to counter shaft 66, the latter serving as the driving shaft for the adhesive applicating mechanism. Shaft 66 is journaled in bearings 67 on frame 26 and carries a spur gear 68 keyed thereto. A pinion 69 secured to brush shaft 62 meshes with spur 68 to effect the rotation of brush 61.

As shown in Figs. 4 and 5, spur gear 68 is provided with a cam lobe 70 on its inner surface which engages the roller 71 carried on one end of rocker arm 72, the latter being pivoted intermediate its ends in a bearing 73 mounted on frame 26. The opposite end 72a of the rocker

arm is connected to a push rod 74 to which each of the operating arms 75 of outlet valves 60 are connected. As spur 68 rotates, cam lobe 70 passes under roller 71 during each revolution causing rocker arm 72 to effect the reciprocation of push rod 74 thereby permitting momentary discharge of the paste from the applicator tank 58 to brush 61.

An even application of the paste is obtained by providing a plurality of outlets 60 spaced along the extent of brush 61, but as further assurance of the even application of paste and also in order to prevent the throw-off of excess paste from brush 61, a guard plate 76 (Fig. 2) is provided adjacent brush 61 which is curved downwardly in general conformance with the contour of the brush to a point just above the upper surfaces of crates C as they pass beneath the brush. While the applicator device illustrated in the drawings is arranged to provide for the continuous cyclical discharge of paste onto the brush, this arrangement may easily be modified to provide for the actuation of the outlet control valves by the passage of the boxes themselves so that paste will be supplied to the applicator brush only at such times as a box actually enters the labeling unit. Such an arrangement is particularly useful where the supply of boxes fed to the labeler may not be entirely uniform, in which case brush 61 may become overloaded with paste between the passage of one box and the next, resulting in the application of an undesired excess of paste to some of the boxes.

After the application of paste to the heads of the crates, the latter are progressed by the gripping action of side chains 30 for a suitable distance to permit operators to manually apply the labels to the crate heads. Upon leaving labeling unit 25, the boxes are transferred to a suitable endless belt conveyer 71, as shown in Figs. 8 and 9, for subsequent delivery to the packing stations. Supported above this conveyer from a pair of uprights 78 is a stationary deflector 79 consisting of a contact bar 80 which depends into the path of upper ends of crates C. As the crates are advanced, they contact bar 80 and are tipped backwardly, to deposit them on their bottoms 23 so that they are thereafter advanced in their reclined position with the open face of the crates extending upwardly.

Various modifications of the labeling unit within the scope of the present invention will be apparent from the foregoing description. As mentioned previously, the use of a lower supporting conveyer is not necessary in many cases. In some instances, also, it may not be necessary to employ a double set of side chains as in the present example, although in the case of boxes, such as the lemon or orange crates described more particularly hereinabove, the multiple sets are preferred inasmuch as a very firm grip can be had on the crates without at the same time

encountering the disadvantage of excessive pressure at any one point, thus causing a rupture of the side members. It is possible also that, in place of the laterally disposed gripping chains, endless belts or a series of short, vertically journaled rollers or drums at each side of the labeler may be employed to support and advance the boxes or crates. In all cases, however, it is essential that the engaging surfaces of the advancing means employed shall be substantially permanently fixed apart a distance which is appreciably less than the normal width of the particular box for which the apparatus is designed, so that by far the greater part of the accommodating action which takes place as the boxes pass between the advancing means must and does occur in the walls of the boxes themselves.

What is claimed is:

A conveyor mechanism adapted for use with labeling devices which exert label-applying pressures at right angles to the path of travel of an up-ended crate to be labelled, said crates comprising rigid end and intermediate walls interconnected by resilient side walls, the combination of: means adapted to advance crates in up-ended position along a selected path of travel; and drive means for said advancing means; said advancing means comprising pairs of vertically spaced endless chain conveyor means, each pair of said conveyor means lying in the same plane and being disposed on opposite sides of the path of travel of said crates; rigid members supporting said chain conveyor means along the entire length of opposed lays in unyielding parallel relation; straight virtually continuous faces on said opposed lays of each pair of chain conveyor means for continuous uniform engagement with resilient walls of said crates and along parallel lines of contacts; said faces being spaced apart a distance less than the normal lateral width of a crate, said crates being maintained in vertical up-ended position by outwardly directed pressure of said resilient walls against said unyielding chain conveyor means.
